Filed Mar. 13, 1972, Ser. No. 234,454

Term of patent 14 years

Int. Cl. D13—03

U.S. Cl. D26—5 R

FIG. 1 is a perspective view of a slide cover for electrical connections embodying my design.

FIG. 2 is an enlarged top plan view thereof.

FIG. 3 is an enlarged bottom plan view thereof.

FIG. 4 is an enlarged end elevational view thereof.

FIG. 5 is an enlarged top plan view thereof shown in an open position.

The broken line disclosure of the wiring in FIGS. 1, 2, 3 and 5, and the broken line disclosure of the electrical connection in FIG. 5 are for illustrative purposes only, and are not a part of the claimed design.

I claim:

The ornamental design of a slide cover for electrical connections, as shown.
